Specification for Design.

Patented Oct. 4, 1921.

Application filed September 13, 1918. Serial No. 254,015. Term of patent 3½ years.

To all whom it may concern:

Be it known that I, GEORGE B. SCOTT, a citizen of the United States, residing in Philadelphia, Pennsylvania, have invented a new, original, and ornamental Design for a Box or Container, of which the following is a specification, reference being had to the accompanying drawing, in which:

Figure 1, is a perspective view of a box or container showing the new and ornamental design forming the subject of my invention.

Fig. 2, is a side elevation of the box or container.

Fig. 3, is an end elevation thereof, and Fig. 4, is a plan view.

I claim:

The ornamental design for a box or container, substantially as shown in the accompanying drawing.

GEORGE B. SCOTT.
